BOTTLE BREAKER

Ralph J. McGill, San Francisco, Calif.

Application October 13, 1937, Serial No. 168,738

3 Claims. (Cl. 83—93)

This invention relates to bottle breakers and has for one of its objects the provision of a simple yet efficient manually operable means for the breaking or defacement of beverage bottles 5 to render them unfit for further use.

The laws of many jurisdictions now require that when alcoholic liquor bottles have been emptied of their original contents they are to be immediately broken to prevent refilling or any other 10 unlawful use of the same as containers. While some of these laws are understood to require that the bottle be smashed, others simply require that the mouth or neck be so defaced as to prevent any further sealing of the container in repetition 15 of the original use. Therefore the present invention contemplates a simple defacement of the neck structure of the bottle.

I am aware of the fact that a number of bottle breakers have been manufactured and offered 20 to the public but I am also cognizant of the fact that these devices are relatively too expensive, or too difficult to operate, or completely ignore the factor of safety and as a result none of them have been universally adopted.

25 It is a well known fact that in the breaking of a glass container of any shape extreme care must be exercised to prevent bodily injury from flying fragments or slivers. There have been many instances of accidents resulting from use of some 30 of the prior art structures and those makeshifts which occur to persons having need of devices of this general character.

With these observations in mind I set about the development of a simple, inexpensive structure 35 which would not only efficiently and conveniently attain the desired results, but which would make suitable provision against injury resulting from the aforementioned causes.

In general my invention comprises a plier-like 40 tool, one end of which is adapted to be inserted in the open mouth of a bottle, the spreading or expansion of which by contraction or operation of the handles will exert sufficient pressure within 45 the bottle neck or mouth to crack or deface that area of the bottle. In addition, my device includes a shield which will serve the purpose of first covering the breakage zone of the bottle and, through the resiliency of the material from 50 which it is made, cause the insertable portion of the tool to be contracted to its original position.

These and other objects will become apparent as the specification proceeds and the novelty of the same will be particularly pointed out in the 55 appended claims.

In the drawings:

Figure 1 is a front elevation of the preferred form of the bottle breaker forming the subject matter of this application.

Figure 2 is a side elevation of the subject matter of Figure 1 with the shield shown in section to disclose the relative position of parts.

Figure 3 is a schematic view showing the manner of operating the tool illustrated in Figures 1 and 2.

Figure 4 is a fragmentary view, partly in section, disclosing the yieldable means (modified form) for returning the tool to its inoperative position.

Figure 5 is a detailed section taken along the 15 lines 5—5 of Figure 4.

Figure 6 is a perspective view from the under-side of a modification of my invention, and

Figure 7 is a top plan view of the modification illustrated in Figure 6.

The device illustrated in Figures 1 to 5, inclusive, is comprised of the plier-like handle members 10 and 11, of identical shape, connected at one of their ends for relative pivotal movement by a pivot pin 12. These handle members, it will 25 be noted, are in the form of intersecting reverse curves.

The members 10 and 11 are so designed that when connected and the handles are spread, or let us say in inoperative position, the ends opposite the handles thereof coincide to define the cone or tapered end section 13. This tapered end is the portion of the tool which is inserted in the bottle neck to effect the desired breakage, as will hereinafter become more apparent. When 30 the tool has been inserted in a bottle neck and the handles are contracted, it will be appreciated that due to the connection of the ends at 12, those portions of the handle extensions forming 35 the insertable end 13 will move with relation to each other and exert pressure on the walls of the bottle neck sufficient to crack or break the same (see Figure 3). The limits of this relative movement are defined by the complementary 40 stops or shoulders 14 on the handle members.

A substantially bell-shaped shield 17 of rubber or like resilient material, serves several purposes in the operation of this bottle breaking tool. In the first place the shield 17 is attached to the 50 tool in the following manner: An annulus or groove 18 is cut into the cone 13 formed by the extensions of the handle members 10 and 11. An axial aperture 19 in the shield 17, of slightly 55 smaller diameter than the cone 13 as reduced

by the groove 18, permits the shield to be slipped over the cone 13 and resiliently engage the same in said groove.

The first function of the shield 17 thus connected to the bottle breaking tool, is to serve as a resilient means to return the handle members 10 and 11 to their spread position after they have been contracted to effect the desired breakage. The second function of the shield 17 is to prevent fragments and slivers of glass from the bottle neck from flying and bodily injuring the operator or those who may be standing nearby. The third function of the shield 17 is as a base for the tool, enabling it to stand in upright position (Figure 1) to be readily grasped.

It will be noted from Figure 3 of the drawings that when the tool is used in conjunction with a conventional alcoholic beverage bottle such as the type illustrated, at 20, the bottom of the shield or rather the mouth of the bell fits very closely about the bottle shoulder when the cone 13 has been inserted in the mouth or neck of the bottle. This serves to effectively prevent fragments or slivers of glass from flying. In case of these beverage bottles having a longer neck portion it will be appreciated that the bell 17 is of sufficient depth to effectively cover the area of the neck likely to be broken upon operation of the tool forming the subject matter of this invention.

Figure 3 also illustrates the distortion of the bell 17 from the shape shown in Figure 2 upon contraction of the handles 10 and 11, and the extent to which a bottle of the type illustrated is defaced by the tool.

Figures 4 and 5 of the drawings illustrate a modification of the preferred form of the invention to the extent that here is provided a supplemental means for urging the parts of the bottle breaker back to normal position after operation and thus relieve the fatigue of the material from which the cone 13 is made.

A slot 21 is cut in the bottom of the groove 18 in cone 13 to receive a circular spring 22. This spring is anchored in the slot 21 through the provision of a tip 23 bent inwardly for accommodation in a hole 24 in the bottom of slot 21.

It will thus be seen that the circular spring 22 underlies that portion of the rubber shield 17 in groove 18 and serves as supplemental means to urge the tool back to its inoperative position (see Figure 1).

In the modified form of the invention illustrated in Figures 6 and 7 of the drawings, I have provided a tool formed of a pair of handle members 30 and 31 connected for relative pivotal movement by a pin 32 inserted through the overlapping ear 33 integral with the respective handle portions 30 and 31.

60 The insertable cone 34, in this instance, is comprised of a pair of half cones 35 and 36, integral with the handle members 30 and 31, respectively, and lying in a plane substantially at right angles to that portion of the handle members bearing 65 the ears 33 for the pivotal connection. Contraction of the handle members 30 and 31 serves to spread the half conical members 35 and 36 (see Figure 7), thus exerting an expanding pressure on the walls of the bottle neck sufficient to cause 70 breakage.

In this particular form of the invention the bell-like shield 17 is attached by frictionally engaging the half conical members 35 and 36 adjacent the point of their connection to the handle

members 30 and 31, or here again the shield 17 may be more securely attached to the tool through the provision of an annulus or groove cut in the cone 34 as in the preferred form illustrated in Figures 1 to 5, inclusive. Moreover, if it is desired to supplement the resiliency of the rubber shield 17 to cause spreading of the handle members 30 and 31 to inoperative position, a spring, such as 22, may be provided in the groove in the cone 34 in precisely the manner illustrated 10 in Figures 4 and 5.

In the modified form of the invention illustrated in Figures 6 and 7 of the drawings it will be noted that the handle members 30 and 31 are tapered upwardly away from the flat area from 15 which the ears 33 project, for the purpose of placing the hand of the operator above the breakage zone and preclude any possibility of danger from those glass fragments or slivers which may escape from the shield 17.

Having thus described my invention, what I claim and desire to secure by grant of Letters Patent is:

1. In a bottle breaking tool, a pair of handle members connected together adjacent their ends 25 for relative pivotal movement from open to closed position, each of said handles having an integral portion, which portions may be closed together by movement of the handle members into their open position to define a member insertable 30 into a bottle mouth, a shield of resilient material having an opening therein through which the insertable members are inserted, the size of the opening in said shield and the corresponding portions of said insertable members being such 35 that the insertable members are normally urged by the resilient shield into their closed position.

2. In a bottle breaking tool, a pair of handle members connected together adjacent their ends 40 for relative pivotal movement from open to closed position, each of said handles having an integral portion, which portions may be closed together by movement of the handle members into their open position to define a member insertable into a bottle mouth, an annular slot in said handle 45 members in spaced relation to their connected ends, a shield of resilient material having an opening therein through which said insertable members are inserted, said shield being seated in said slot, the size of the opening in said shield and the size of the handle members as reduced 50 at said slot being such that the insertable members are normally urged by the resilient shield into their closed position.

3. In a bottle breaking tool, a pair of handle 55 members connected together adjacent their ends for relative pivotal movement from open to closed position, each of said handles having an integral portion, which portions may be closed together by movement of the handle members into 60 their open position to define a member insertable into a bottle mouth, an annular slot in said handle members in spaced relation to their connected ends, a coil spring in said annular slot, a shield of resilient material having an opening 65 therein through which said insertable members are inserted, said shield being seated in said slot, the size of the opening in said shield and the size of the handle members as reduced at said slot being such that the insertable members are normally urged by the resilient shield and said coil spring into their closed position.
